UNITED STATES PATENT OFFICE

WALTER F. HEROLD, OF BRIDGEPORT, CONNECTICUT, ASSIGNOR TO THE BASSICK COMPANY, OF BRIDGEPORT, CONNECTICUT, A CORPORATION OF CONNECTICUT

CUSHION SLIDE FOR FURNITURE

Application filed April 30, 1931. Serial No. 533,881.

The present invention relates to cushion slides for furniture, and has for an object to provide a slide of simple and inexpensive construction and which may be attached with facility, merely by driving with a hammer. Another object is to provide a cushion slide which will permit tilting of the furniture without loosening, and which will at all times remain firmly in place without looseness or rattling, irrespective of whether the slide is in engagement with the floor or not. A further object is to provide a slide having an attaching nail loosely but permanently secured to the metal shoe of the slide, and to this end I propose to secure the same by swedging the metal of the shoe in a manner to greatly facilitate assembly and provide a reliable connection between the shoe and the nail. With the above and other objects in view, an embodiment of the invention is shown in the accompanying drawing and this embodiment will be hereinafter more fully described with reference thereto and the invention will be finally pointed out in the claims.

In the drawing:

Fig. 1 is a side elevation of a cushion slide according to the illustrated exemplary embodiment of the invention.

Fig. 2 is a plan view thereof.

Fig. 3 is a vertical sectional view, showing the same attached to a furniture leg.

Fig. 4 is a similar view showing a tilted position of the leg.

Fig. 5 is a sectional view of the metal shoe, before assembly of the attaching nail.

Fig. 6 is a similar view showing the nail assembled to the shoe.

Similar reference characters indicate corresponding parts throughout the several figures of the drawing.

Referring to the drawing, the cushion slide, according to the present embodiment of the invention, comprises a metallic base or shoe 10, preferably of circular form, hav-

ing a flat upper surface 11, and a slightly convex lower floor-engaging surface 12. A socket 13 is provided centrally of the upper surface having its side walls contracted at the top, and within this socket the head 14 of the driving nail 15 is loosely engaged and retained, the dimensions of the socket being such as to allow free up and down and tilting movement of the nail.

At the upper side of the shoe a cushion layer 16 is provided, which may be of soft rubber, cork, or other suitable material, the same conforming at its outer periphery to the shoe and having a central aperture 17 engaged by the nail.

A metallic washer 18 of smaller diameter than the cushion layer is engaged upon the nail at the upper side of said cushion layer, being tightly pressed upon the nail and retained against retrograde movement by the bur 19 of its central aperture 20 forced up upon the surface of the nail, the latter preferably having its surface provided with barbs, corrugations, or teeth 21.

In Figs. 5 and 6 I have shown the manner of assembling the nail and metal shoe. The side wall of the socket 13 is cylindrical, before assembly, and an upstanding flange 22 is provided at its upper edge. The nail head is inserted in the socket and by means of a suitable swedging tool the flange 22 is flattened, causing the inner wall of the socket to contract at its upper end, so that the nail head is locked in place.

The operation is as follows:

Before attachment to the leg the parts of the slide are in the relation shown in Fig. 1, with the head of the nail engaging the base of the socket 13 and the washer 18 engaging the upper surface of the cushion layer and predeterminedly positioning the nail in such relation. In driving the nail into the furniture leg the blows directed against the surface 12 of the metal shoe 10 are directly transmitted to the nail head, so that the same may be

firmly and accurately driven. As the washer 18 comes into contact with the end of the leg a further driving of the nail forces the washer downwardly upon the nail and the cushion layer is compressed, so that upon its expansion after the driving operation the head of the nail assumes a position in spaced relation above the base of the socket 13, as clearly indicated in Fig. 3, permitting up and down and tilting movement of the leg, the shoe remaining substantially flat upon the floor.

I have illustrated and described a preferred and satisfactory embodiment of the invention, but it will be obvious that changes may be made therein within the spirit and scope thereof, as defined in the appended claims.

Having thus described my invention what I claim and desire to secure by Letters Patent is:—

20 1. A cushion slide for furniture, comprising a floor engaging shoe, attaching means adapted to be driven into the furniture connected to said shoe and having free up and down and tilting movement relative to said shoe, a cushion layer at the upper side of said shoe, and a non-flexible and non-compressible washer frictionally engaged on said attaching means at the upper side of said cushion layer and adapted to yieldably retain said attaching means in a predetermined position relative to said washer, said washer adapted to have movement on said attaching means only toward said shoe, said attaching means adapted to be driven by blows applied to said shoe.

40 2. A cushion slide for furniture, comprising a floor engaging shoe having a closed lower side and having a socket in its upper side provided with a flat base, attaching means comprising a nail adapted to be driven into the furniture and having a flat head retained in said socket and having free up and down and tilting movement relative to said shoe, and a cushion layer at the upper side of said shoe, said attaching means adapted to be driven by blows applied to the lower side of said shoe and whereby said flat base of said socket engages said flat nail head to maintain said nail perpendicularly relative to said shoe during driving.

50 3. A cushion slide for furniture, comprising a floor engaging shoe having a closed lower side and having a socket in its upper side attaching means adapted to be driven into the furniture retained in said socket and having free up and down and tilting movement relative to said shoe, a cushion layer at the upper side of said shoe, and a washer frictionally engaged on said attaching means at the upper side of said cushion layer adapted before attachment to predeterminedly position said attaching means to engage with the base of said socket when said cushion layer is engaged with the upper side of said shoe, said attaching means adapted to be driven

and be moved relatively to said washer by blows applied to the lower side of said shoe.

4. A cushion slide for furniture, comprising a floor engaging shoe, attaching means adapted to be driven into the furniture connected to said shoe and having free up and down and tilting movement relative to said shoe, a cushion layer at the upper side of said shoe, and a non-flexible and non-compressible washer frictionally engaged on said attaching means at the upper side of said cushion layer adapted to retain said attaching means in a predetermined position relative to said washer against the pressure of the latter when compressed, said attaching means adapted to be driven and be moved relatively to said washer by blows applied to said shoe.

5. A cushion slide for furniture, comprising a non-resilient floor engaging shoe having a lower substantially non-tilting floor-engaging surface and having an upwardly facing centrally disposed non-resilient positioning portion in its upper side, attaching means comprising a shank adapted to be inserted into the furniture and having its lower end engaged with said positioning portion and adapted to have universal tilting and unrestricted rotary movement relatively thereto, the engagement of said lower end with said positioning portion constituting a centralizing fulcrum about which said shank has its tilting movement, said shoe being outwardly spaced from said shank whereby universal tilting movement of said shank is permitted to a substantial degree without restriction by said shoe, a resilient cushion body at the upper side of said shoe adapted to be interposed between the furniture and the shoe to space them apart and permit cushioned relative tilting movement, and a washer mounted on said shank at the upper side of and engaging said resilient body, and movable with the tilting movement of said shank whereby said resilient body is compressed between said washer and said shoe at its portion disposed in the direction of tilt.

6. A cushion slide for furniture, comprising a non-resilient floor engaging shoe having a lower substantially non-tilting floor-engaging surface and an upwardly facing centrally disposed non-resilient positioning portion in its upper side, attaching means comprising a shank adapted to be inserted into the furniture and having its lower end engaged with said positioning portion and adapted to have universal tilting and unrestricted rotary movement relatively thereto, the engagement of said shank with said positioning portion constituting a centralizing fulcrum about which said shank has its tilting movement, a resilient cushion body at the upper side of said shoe adapted to be interposed between the furniture and the shoe to space them apart and permit cushioned relative tilting movement and having a cen-

tral aperture engaged by said shank, the lower end of said shank having a circumferential flat under surface adapted to engage flatly against a horizontally disposed circumferential flat portion of said shoe, whereby said shank stands perpendicularly to said shoe when said lower end is flatly engaged therewith.

Signed at Bridgeport, county of Fairfield,
10 and State of Connecticut, this 8th day of
April, 1931.
